Primary Examiner — Robin V Webster(74) *Attorney, Agent, or Firm* — Nelson Mullins Riley & Scarborough LLP(57) **CLAIM**

The ornamental design for the sensitive plant sprayer, as shown and described.

DESCRIPTION

FIG. 1 is a perspective view of a sensitive plant sprayer in accordance with an embodiment of the present invention; FIG. 2 is a bottom view of the sensitive plant sprayer of FIG. 1;

FIG. 3 is a top view of the sensitive plant sprayer of FIG. 1; FIG. 4 is a left side view of the sensitive plant sprayer of FIG. 1;

FIG. 5 is a right side view of the sensitive plant sprayer of FIG. 1;

FIG. 6 is a front view of the sensitive plant sprayer of FIG. 1; and,

FIG. 7 is a back view of the sensitive plant sprayer of FIG. 1.

The broken lines of FIGS. 1-7 are illustrative of the visible environmental structure of the sensitive plant sprayer and form no part of the claimed design.

1 Claim, 6 Drawing Sheets(56)
